UNITED STATES PATENT OFFICE

172,906

XEROGRAPHIC PROCESSOR

Edward R. Sabel, Clyde R. Mayo, and Joseph Douglas Guite, Rochester, N. Y., assignors to The Haloid Company, Rochester, N. Y., a corporation of New York

Application October 23, 1953, Serial No. 27,300

Term of patent 14 years

(Cl. D61—1)

To all whom it may concern:

Be it known that we, Edward R. Sabel, Clyde R. Mayo, and Joseph Douglas Guite, citizens of the United States of America, residing at Rochester, State of New York, have invented a new, original, and ornamental Design for Xerographic Processor, of which the following is a specification, reference being had to the accompanying drawing, forming a part hereof.

Fig. 1 is a front perspective view of a xerographic processor, showing our new design;

Fig. 2 is a front perspective view thereof, in open position; and

Fig. 3 is a side elevation view thereof.

The side not shown is the same as the side shown. The back is plain.

What is claimed is:

The ornamental design for a xerographic processor, as shown and described.
